UNITED STATES PATENT OFFICE.

SAMUEL J. BELL, OF SPRINGFIELD, MASSACHUSETTS.

CHANGE-MAKING MACHINE.

1,424,439.

Specification of Letters Patent. Patented Aug. 1, 1922.

Application filed September 15, 1920. Serial No. 410,462.

To all whom it may concern:

Be it known that I, SAMUEL J. BELL, a citizen of the United States of America, and a resident of Springfield, in the county of 55 Hampden and State of Massachusetts, have invented a new and useful Change-Making Machine, of which the following is a specification.

My invention relates to improvements in 10 machines for automatically making change with coins upon operating certain levers or keys, and consists of the parts and the combinations of parts substantially as herein-after described.

15 The primary object of my invention is to produce a change-making machine for handling coins, which machine is especially adapted for use on street-cars, motor-busses, and other vehicles wherein the passengers 20 pay as they enter or leave the vehicle, to the end that a very great amount of time is saved, both to the conductor or motorman who receives the fares and to the passengers who 25 pay them, and a large amount of money for the vehicle owner.

Another object is to provide a machine of this type which delivers the fare belonging to the company directly to the fare-box, so that the operator in making change has occasion to handle no money except that belonging to the passengers.

30 Still another object is to provide such a machine which consists of few parts, is comparatively simple in construction, not liable to get out of order or to be broken, and extremely simple in operation.

40 A further object is to produce a machine that is capable of handling coin-units of two or more coins, instead of such units each of which actually consist of a single coin, and of handling as well coin units of two or more coins of different denominations.

An additional object is to afford means in 45 the machine for handling successfully coins which vary in thickness, due to the fact that some are new or of standard thickness and others are worn and therefore thinner than the former.

50 The machine can be operated rapidly and even at utmost capacity by any one after having the operation explained to him and experimenting or practicing a short time.

55 The machine as here presented is designed to handle 7-cent fares, and to make change for a quarter of a dollar, and for a dime, and at the same time deposit seven cents out of

either the quarter or the dime, so to speak, in the fare-box. The mechanism is also adapted to deliver pennies independently. By making the necessary changes in the machine, which changes, however, do not affect the principle of the invention or materially alter the construction of the machine as a whole, said machine can be made to handle 60 6-cent fares, 8-cent fares, and fares of other denominations, and also to change other denominations besides nickels, dimes and quarters.

Although my machine is especially adapted for use on passenger-carrying vehicles, 70 it is equally well adapted for use at the entrances of buildings or grounds where admission fees are collected and it is necessary to make change; in short, the machine can, 75 be used successfully and advantageously wherever it is required to make change easily and expeditiously.

Other objects and advantages will appear in the course of the following description.

A preferred embodiment of my invention, 80 whereby I attain the objects and secure the advantages of the same, is illustrated in the accompanying drawings, and I will proceed to describe the invention with reference to said drawings, although it is to be understood that the form, construction, arrangement, etc. of the parts in various aspects are 85 not material and may be modified without departing from the spirit of the invention or exceeding the scope of what is claimed.

90 In the drawings, in which like numerals designate like parts throughout the several views, Figure 1 is a front elevation of a change-making machine which embodies my invention as aforesaid, a portion being broken away; Fig. 2, a right-hand end elevation of said machine; Fig. 3, a front elevation of the lower part of the machine looking into the case, certain parts having been removed; Fig. 4, a top plan of certain parts 95 of the machine, parts having been removed, and others shown in section; Fig. 5, an enlarged, horizontal section through said case; Fig. 6, a sectional detail through the coin-chute which delivers the coins to the fare-box, and showing an inside end elevation of one of the other coin-chutes; Fig. 7, an enlarged, end elevation of the lock rod; Fig. 8, an enlarged, bottom plan of the delivery slides, the supporting members therefor, and other associated parts; Fig. 9, an enlarged 100 vertical section through the bottom part of

the machine, taken on a plane in which is the axis of the left-hand magazine; Fig. 10, an enlarged detail, in vertical section, and Fig. 11, an enlarged, sectional detail of certain members of the operating mechanism.

Before describing in detail the machine as illustrated in connection herewith, it is desired to state that, in practice, said machine is customarily used in connection with a fare-box, and is supported in position to discharge the fares into such box. Special means of supporting the machine may be provided, and also a special fare-box; but when the machine is installed in a street-car, for example, that is equipped with the regulation fare-box and register, said machine may be attached to the same rod to which said fare-box and register are attached.

The operating mechanism of this change-making machine is contained within a suitable case 1. Rising from the ends of the case are two uprights 2 which are connected at the top by a cross-piece 3. The front of the case consists of a plate 4 which has end-pieces 5 and is provided with three forwardly- and downwardly-extending coin-chutes 6, 7, and 8, and with a coin-chute 9 which extends downwardly and outwardly from the right-hand end-piece. The plate 4 has an upward and forward inclination as best shown in Fig. 9. The coin-chutes 6, 7, and 8 may be termed change-chutes, because it is through them that the change passes into the hands of the operator. The coin-chute 9 may be termed a fare-chute, since through this the fares pass into the fare-box of which mention has been made. These coin-chutes are all open at their outer ends, and they are also open at their inner ends inside of the case. There are three vertical slots 10 in the plate 4, two of such slots being between the change-chutes and the third slot being at the right of the right-hand change-chute. Although the change-chutes are alike, they are given different numerals in order to facilitate the explanation of the operation of the machine.

The uprights 2 are at the front of the case 1, and behind these uprights is a top plate 11. Extending between the ends of the case is a thick bar 12 (Fig. 4), and in said bar are four vertical openings 13. Said openings are in line with each other from left to right, they are equi-distant apart, and the left-hand opening and the two openings at the right thereof are in the same vertical, parallel planes with the vertical centers of the change-chutes 6, 7, and 9, such planes extending from front to rear. On the bottom of the bar 12 at the ends and contiguous to the ends of the case are two guide-bars 14, each having on the inside thereof a rib 15; and on said bottom of said bar, between said guide-bars, and spaced equi-distantly from the latter and from each other are

three guide-bars 16, each of which has on opposite sides thereof ribs 15 that are similar to the ribs 15 on said first-named guide-bars. The guide-bars 14 and 16 are all parallel with each other.

The machine in this case is equipped with four coin magazines which comprise, with the perforated portions of the bar 12, the same number of tubes 17, 18, 19, and 20, different numerals being here employed for parts that are essentially similar, as is done in connection with the change-chutes on the front of the case, and for a similar reason. Each of the aforesaid tubes is seated at its base in one of the magazine openings 13, the sides of which are shouldered at 21, Figs. 9 and 10, to receive said base, and the top of said tube is received in an opening in the cross-piece 3, or attached to said cross-piece in registry with such openings. Thus the magazine tubes are supported by the bar 12 and the cross-piece 3 of the frame on the case. A cover 22 is provided for the open upper end of each magazine, said cover being pivotally attached at 23 to the cross-piece 3, and adapted to be turned aside on its pivot to open said upper end for the introduction of coins at that point, and also in the event it be desired to empty the coins out of the magazine at the top.

In the front of each magazine tube is a central, vertical series of large holes 24, and two flanking, vertical series of small holes 15, through which the coins in said reservoirs are visible and the number thereof ascertainable.

The diameters of the magazines may vary, inasmuch as each magazine has a diameter that is a little larger than that of the largest coin which is receivable therein.

A set of coin cut-off and delivery slides is provided beneath the plate 12. There is the same number of such slides as magazines, and said slides are designated, commencing with the left-hand one, by the numerals 26, 73, 74, and 75. Each of said slides has a vertical opening 27 therein of the same diameter as that of the associated opening 13 in the plate 12 above, and, when said slide is at the rear end of its travel, the opening therein is in exact registry with said plate opening. Each slide has grooves in the sides thereof to receive the guide-bar ribs 15, and said slide is adapted to be reciprocated between the contiguous guide-bars (14-16). A cross-bar or abutment 28, on the back side of the case inside, is in proper position to limit the backward movement of the slides. The openings 27 are in the forward portions or adjacent to the front edges of the slides. In the undersides of the slides 26, 73, 74, and 75, respectively, are wide slots 29, 76, 77, and 78. These slots extend inwardly some distance from the front edges of the slides, and the openings 130

27 are above and at their lower ends open into said slots.

Each of the slides is normally retained at the rear end of its travel, with the back edge thereof in contact with the abutment 28, by means of a pair of springs 30, which springs are attached at their rear ends to staples 31 that depend from the bottom of said abutment, and at their forward ends 10 to pins 32 which depend from the bottom of the slide adjacent to the front edge thereof and both sides of the slot therein.

On the floor of the case 1 are four base-pieces 33 the axial centers of which, if continued upwardly, would coincide with the axial centers of the coin magazines. Each base-piece has a vertical opening 34, Fig. 9, in the center thereof, and the sides of this opening are tapped to receive the threaded 20 lower terminal of a post 35. Each post is provided at the top with a coin-supporting platform 36. The platforms extend into the slots in the undersides of the slides, directly beneath the openings 27 in said 25 slides, and normally support the columns of coins in the magazines above. The tops of the slots in the slides are in contact with the tops of the platforms, so that the coins cannot escape laterally between contiguous 30 parts of said slides and platforms. Neither can the coins escape laterally from between any slide and the bar 12, even though some clearance is left between the two for the purpose hereinafter set forth, provided such 35 clearance be of less width than the thickness of any coin which might otherwise escape.

It will now be seen that the axis of each coin magazine, if continued downward, would pass through the axis of the opening 40 27 in the slide below, provided said slide be in retracted position, and coincide with the vertical centers of the platform and post below, and that the column of coins in such magazine is carried normally on one of said 45 platforms.

The slotted parts of the slides are made of different thicknesses so that the distances between the bottom of the bar 12, which is the cutting-off plane for the columns of 50 coins, and the tops of the several platforms may be varied and made to equal approximately the combined thicknesses, respectively, of the pluralities of coins that make up the coin-units which rest on and are to 55 be removed from such platforms.

The term coin-unit as herein used is the equivalent generally of either the term change-unit or fare-unit as herein employed.

Each of the magazines 17 and 18 is designed to contain a column of pennies, while each of the magazines 19 and 20 is designed to contain a column of mixed pennies and nickels, and said last two magazines necessarily must each be larger in diameter than 60 either of said first-named magazines. The

coins in the magazine 19 must be arranged in the order of three nickels and three pennies, so that each change-unit will equal 18 cents. It is not of great importance in what manner the pennies and nickels are relatively placed or stacked, provided there be in each unit of six coins, three nickels and three pennies, although it is preferable that a nickel, which is the larger coin of the two involved in the present case, should be at the top of 70 each change-unit, for the reason that the cutting-off operation is thereby facilitated, there being less lost motion involved in said operation than there would be if one of the smaller coins were to receive the shearing stroke of the operating slide. The coins in the magazine 20 are arranged so that there shall be in each fare-unit, in said magazine, a nickel and two pennies. These also might be arranged in any convenient 75 manner or without reference to any particular order, were it not for the fact that here again it is preferable to have a nickel at the top of each fare-unit in order to facilitate the cutting-off operation. The columns 80 of coins in the magazines normally resting at their bottoms on the platforms 36, are supported at exactly the proper elevations, relative to the bottoms of said magazines, by said platforms. The platforms are adjusted through the medium of the posts 35 by rotating said posts in the base-pieces 33 to raise or lower them and with them said platforms, so as to locate the latter in proper relation to the portions of the cut-off and delivery 90 slides that are above and in contact with said platforms, which portions, it will be remembered, are of different thicknesses. The posts 35 may be provided with lock-nuts 95 79 to hold them against rotation after they are adjusted.

Although the units of coins which are delivered from the magazine 20 by the slide 75, to the fare-chute, are as much change-units as are the change-units delivered from 100 the other magazines, by the other slides, to the change-chutes the former are designated as fare-units because they are discharged from said fare-chute into a fare-box, and constitute actual fares, while the other units 115 of coins are discharged into the hand of the operator who gives them to the persons for whom he is making change.

If all coins used in this machine were of 120 standard size, as when they leave the mint, instead of some of them being of such size and others being thinner from wear, the upper surfaces of the cut-off and delivery slides might be in rubbing contact with the bottom surface of the bar 12, since in that event 125 the shear line for the coin-units would be at such plane of contact, assuming, of course, that said slides be of the proper thicknesses in their forward portions, and that the platforms 36 be properly adjusted. Such is not 130

the case, however, because the coins become thin through wear, and, if a coin-unit at the bottom of any column of coins should contain even a single coin which is appreciably 5 thinner than standard thickness, the coin-unit above would be positioned so low that the bottom coin in said last-named unit would lock the slide.

To obviate the difficulty just pointed out, 10 and make the machine capable of handling coins of any variety of thickness, within ordinary and reasonable bounds, I provide a clearance between the cut-off and delivery slides and the bar 12 in each case, such 15 clearance appearing at 71—71 and 80—80— see Figs. 3 and 9. The clearances 71 are between the slides 26 and 73 and the bar 12 above, and the clearances 80 are between the slides 74 and 75 and said bar. Each space 20 71 in width is slightly less than the thickness of a penny, while each space 80 in width is a little less than the thickness of a nickel. The spaces 71 and 80 thus provided and proportioned relative to the coins compensate 25 for any reasonable variation in the height of the change- and fare-units, and insure a free unobstructed cutting-off action on the part of the machine and the certain removal of the units from their respective columns, 30 because the cutting-off plane for any bottom unit in its column is always at some point below the bottom surface of the bar 12 and above the top surface of the operating slide for such unit. Locking of the parts with 35 a coin is thus practically entirely prevented.

The spaces 80 would be proportioned to pennies instead of nickels, if it were not the practice to have nickels at the tops of the change- and fare-units in the slides 74 and 40 75 and magazine 19 and 20 against which to shear.

When any cut-off and delivery slide is actuated to the forward end of its stroke, it carries with it the coins which make up 45 the bottom coin-unit in the column of coins above, which unit is in the opening 27 in said slide and resting on the top of the platform 36 below, and pushes the coins in said unit forward on and off over the front edges 50 of said platform, when the coins comprising said unit drop into the coin-chute which is in position to receive them. Each of the cut-off and delivery slides is in position to be actuated forward until the opening 27 there- 55 in is over the open mouth or entrance to some one of the coin-chutes. When any cut-off and delivery slide is advanced to the forward end of its stroke, it occupies the position shown in full in Fig. 10 and in broken 60 lines in Fig. 9, and in the latter view the five pennies, which constitute the change-unit represented as having been just delivered from the magazine 17 by the slide 26, are shown in broken lines dropping into the 65 coin-chute 6.

As soon as any cut-off and delivery slide moves forward far enough to carry the coin-unit, in the opening 27 in such slide, beyond the column of coins above, said column drops on to the slide behind said opening and is 70 supported thereon until the slide is retracted, when said column drops again and deposits another coin-unit in the opening in readiness for the next delivery stroke of the slide. Thus it is seen that the slides not only cut- 75 off and deliver the coin-units, but also serve as temporary supports for the columns of coins. The abutment 28 is so proportioned and located that it stops each slide on its return at the proper place to locate the opening therein exactly under the magazine above.

The interior diameter of each magazine should be a trifle greater than that of the coins which it is designed to contain. This 85 is so that there will be no undue frictional resistance and consequent clogging when it is loaded with coins, and as the ever shortening column descends onto the platform below upon each removal of the bottom units. 90

It is preferable to have a nickel as the top coin of each change-unit in the magazine 19 and as the top coin of each fare-unit in the magazine 20, for the reason that the nickel more nearly fills the space circumfer- 95 entially in the opening 27 in either slide 74 or 75, so that, when said slide is advanced, there is very little lost motion between the sides of said opening and said nickel. If a penny were at the top of the coin-unit, 100 there would be more lost motion in the cutting-off operation, and a tendency, however slight, to retard or render the operation less smooth than in the other case, especially at such times as the magazine above is full or 105 nearly so.

The spaces 71 and 80 must in no case be of a width equal to the thickness of even a thin coin, or in any event of a width sufficient to enable the bottommost coin in the 110 coin-unit next above any given bottom coin-unit to escape between adjacent surfaces of the slide involved and the bar 12, when the former is actuated into its forward position, otherwise such bottommost coin would become displaced and serious difficulty result. It is this bottommost coin that rests on the slide beneath while delivery is being made and until it, with the coins in the coin-unit of which it forms a part, drops in the opening 27 in said slide. The arrangement, construction, and proportions of the parts are such that in all cases the cut-off line or plane for the coin-units is at some horizontal plane within one of the spaces 71 or 80 or between 115 the bottom of the bar 12 and the tops of the cut-off and delivery slides.

The perforated part of the slide 74, which is beneath the magazine 19, is necessarily thicker than such parts of the other slides, 120

because three nickels and three pennies are delivered each time that slide is operated; while the slide 73 beneath the magazine 18 is the thinnest, because with this slide only three pennies are delivered at each forward movement of the same. The slide 75 beneath the magazine 20 is of a thickness in its perforated part to handle a nickel and two pennies at each forward stroke, and the slide 26 beneath the magazine 71 is of a thickness in its perforated part to enable the same to cut off and deliver five pennies.

A column of pennies is clearly represented at 72 in Fig. 9.

15 In the bottom of the case 1, behind the vertical plane in which the base-pieces 33 are located, is a bearing 37 adjacent to the left-hand end of said case, a bearing 38 adjacent to the right-hand end of said case, 20 and an intermediate bearing 39. Journalized in these bearings is a rock-shaft 40. Loosely mounted on the rock-shaft 40, adjacent to the bearing 37, is a sleeve 41 which is provided at the end next to said bearing with 25 an upwardly-extending arm 42, and at the other end with a forwardly- and upwardly-extending arm 43. Secured, by a set-screw 44 or any other suitable means, to the rock-shaft 40, between the sleeve 41 and the bearing 39, is a sleeve 45. The sleeve 45 is provided with an upwardly-extending, intermediate arm 46, and at the right-hand end with a forwardly- and upwardly-extending arm 47, the latter being adjacent to the left- 30 hand side of the bearing 39. Secured to the rock-shaft 40, by another set-screw 44 or other suitable means, is a hub 47 from which an arm 48 extends upwardly. The hub 47 is adjacent to the bearing 38. Loosely 35 mounted on the rock-shaft 40, between the hub 47 and the bearing 39, is a sleeve 49. The sleeve 49 has an intermediate, forwardly- and upwardly-extending arm 50, and is provided at the right-hand end, which 40 is adjacent to the hub 47, with an upwardly-extending arm 51, and at the left-hand end, which 45 is adjacent to the left-hand side of the bearing 39, with an upwardly-extending arm 52. The arms 43, 47, and 50 constitute 50 the operating levers or keys of the machine.

When the arm or lever 43 is depressed, the sleeve 41 is rocked forward on the rock-shaft 40, without affecting the latter, and carries with it the arm 42; when the arm 55 or lever 47 is depressed the sleeve 45 is rocked forward and carries with it the arm 46, and the arm 48 also, inasmuch as said last-named sleeve and said last-named arm are secured to said rock-shaft, and the latter is rocked 60 forward with said sleeve 45; and when the arm or lever 50 is depressed the sleeve 49 is rocked forward on said shaft, without affecting the latter, and carries with it the arms 52 and 51.

65 The arms 42, 46, 52, 51, and 48 are simi-

lar to each other in construction, and so also are the keys 43, 47 and 50. The said keys extend through the slots 10 in the front plate 4, and are provided at their protruding terminals with thumb-pieces 53. Each 70 thumb-piece is pivotally attached at 54 to its key. The thumb-pieces are loosely connected with their keys, in order that the former may maintain a more or less horizontal position when the said keys are depressed, 75 as the operator's thumb is then less liable to slip off said thumb-pieces. The upper surfaces of the thumb-pieces are made convex longitudinally to afford better bearing surfaces for the thumb.

The slots 10 are of sufficient length to enable the keys 43, 47, and 50, which normally are at the top of said slots, to be depressed to the full extent required.

80 Three resilient, flat links 55 connect the arms 42, 46, and 52 respectively with the slides 26, 73, and 74, and similar links 56—56 connect the arms 51 and 48 with the slide 75. The rear terminal of each of the links 55 and 56 is connected with its respective 85 slide by means of a screw 57, a washer 58 being interposed between said link and slide; and the forward terminal of each of said links is connected with the upper end of its respective arm by means of a screw 59 90 which passes downwardly through the link and is tapped into the arm—see Figs. 9 and 11. The passages tapped into the upper terminals of the arms, to receive the screws 59, appear at 60 in Fig. 5, while the openings in the links 55 for said screws appear at 61 in Fig. 8. In place of the openings 61, the links 56 have longitudinal slots 62 therein to receive and accommodate the screws 59, such slots being shown in Figs. 100 105 8 and 11. These slots are required in order to permit the slide 75 to be actuated by either the arm 51 or the arm 48 and the connecting link 56, without affecting the link 56 which connects the other arm with said 110 slide.

When the key 43 is depressed, the slide 26 is actuated forwardly, against the resiliency of the springs 30 connected therewith, through the medium of the sleeve 41, 115 the arm 42, and the connecting link 55, as will be clearly seen upon referring to the broken-line position of the parts in Fig. 9. Upon releasing the key 43 the associated 120 springs 30 retract the aforesaid slide and restore the parts to initial position.

When the key 47 is depressed, it acts through the sleeve 45, and the hub 47, to actuate the slides 73 and 75 forwardly through the medium of the arms 46 and 48 and the 125 connecting links 55 and 56, said slides being operated against the force of their springs as in the first instance, and being returned to normal or initial position upon the release of said key.

When the key 50 is depressed, it operates through the medium of the sleeve 49, the arms 52 and 51 which are rigidly connected with said sleeve, and the connecting links 55 and 56 to actuate the slides 74 and 75 forwardly, against the resiliency of their springs. Upon the release of the key 50 the slides actuated thereby are returned to initial position by means of the said springs.

10 The cut-off and delivery slide, in every case when returning to initial position under the force of its springs, carries with it the operating parts and restores the same to normal position.

15 When the arm 48 is moved to actuate the slide 75, it does so through the medium of the connected link 56, and at that time the left-hand link 56 moves forward without disturbing the arm 51, because the screw 59 which connects said last-named link with said last-named arm is in the slot 62 in said left-hand link, so that the latter is enabled to move forward without taking the screw with it or affecting said arm 51. So, also, 25 when the arm 51 is operated to actuate the slide 75, the right-hand link 56 is moved forward without disturbing the arm 48.

A lock is provided for the cut-off and delivery slides to prevent them from being

30 actuated forward, and thus prevent the machine from being operated to discharge the coins therein. Obviously, if the slides 26 and 75 be locked so that they cannot be actuated forward, the intervening mechanism 35 causes the slides 73 and 74 also to be locked, and to this end I have provided a simple locking device which comprises a rod 63 having thereon two radial lugs 64 to enter corresponding recesses 65—65 in said first-named two slides, special reference being 40 had in this connection to Figs. 4, 7 and 9. The rod 63 is journaled at the left-hand end in a block 66 which is secured against the corresponding end of the case 1, above the 45 guide-bar 14 at that end, and at the right-hand end journaled in the corresponding end of said case, there being a key-hole 67, Fig. 2, in said last-named end to afford access, by means of a suitable key not herein 50 shown, to said rod. The lugs 64 are in position to enter the recesses 65 in the outside slides, when said rod is partially rotated to throw said lugs into said recesses.

In the drawings the lugs 64 are represented as being in their unlocked position and in front of the rod 63.

The rod 63 is rocked in the directions to lock and unlock the slide by means of the key inserted in the key-hole 67 to enter a 60 suitable slot 82, Fig. 7, in the right-hand end of said rod. A lug 68 is located on the same side of the rod 63 with the lugs 64, and adapted to encounter one of the slides, as soon as said lugs 64 have been carried into a 65 forward position, and thus limit the unlock-

ing movement of said rod, and decrease the amount of movement of the rod in locking and unlocking the slides.

Flat surfaces 69 are provided on opposite sides of the rod 63, to be engaged by a 70 spring 70 and thereby retain said rod in either locked or unlocked position. The spring is securely attached to the back side of the bar 12 and has a horizontal part which extends into operative position beneath the rod 63. The spring does not prevent the rod from being rocked in its bearings, but when either flat surface 69 is in contact with said spring the latter holds the rod against rotation, unless sufficient force 75 be applied to overcome the resistance offered by the spring.

It is to be understood that any other suitable lock may be substituted for that herein shown and described, or the lock may be 80 omitted altogether.

Having described in detail the construction of the several parts of the machine, and the operation of the same, it remains only to give a brief explanation of the operation of 90 the machine as a whole, it being assumed that the magazines have been loaded, and that the cut-off and delivery slides have been unlocked.

If five pennies are desired in change for 95 a nickel, the operator places the thumb of one of his hands on the thumb-piece 53 of the key 43, holds the palm and fingers of the same hand under the coin-chute 6, and presses said key to the lower end of its slot 100 10. This action causes the slide 26 to advance, with the five pennies in the opening 27 therein, and to deliver said pennies to said chute, which in turn discharges them into the extended hand below.

105 When a dime is to be changed, from which seven cents is to be deposited in the fare-box, the operator presses down the key 47, in the same way as before, and so causes the slides 73 and 75 to advance, with the result 110 that three pennies are discharged into the hand of the operator, by said slide 73 and from the coin-chute 7, and seven cents (one nickel and two pennies) are delivered by said slide 75 to the coin-chute 9, and discharged thereby into the fare-box.

115 Upon the presentation to the operator of a quarter of a dollar from which one 7-cent fare is to be taken, he depresses the lever 50, and by so doing receives eighteen cents 120 (three nickels and three pennies) in his hand, and causes seven cents to be delivered to the fare-box as before, the slide 74 delivering the change-unit to the coin-chute 8, through which these coins pass into the 125 hand, and the slide 75 delivering the fare-unit to the coin-chute 9.

To obtain two 7-cent fares and the proper change from a quarter, it is necessary to depress the key 47 twice, which causes fourteen 130

cents to be discharged into the fare-box, and six cents to be discharged into the hand, and then to depress the key 43, which causes five pennies to be added to the six pennies already ready in the hand, thus making up the eleven cents change after the two 7-cent fares have been taken out. Any other order of depressing the keys 47 and 43, to obtain two fares and the change from a quarter, may be 10 sorted to.

The forward movement of each of the cut-off and delivery slides is limited by the back end of the slot (29, 76, 77, or 78) therein, which encounters the corresponding side of 15 the associated platform 36 when the slide arrives at the forward end of its travel. Such movement may be limited also by the bottom end of the slot 10 in which the operating key lever (43, 47, or 50) is located.

20 What I claim as my invention, and desire to secure by Letters Patent, is—

1. In a change-making machine, magazines for columns of coins, delivery means for coins from one of said magazines, delivery means for coins from the others of said magazines, the points of discharge of such delivery means being remote from each other, movable means in operative relation to each of said magazines, actuating means 25 for the means associated with certain of said magazines, the movable means associated with one of said magazines being without actuating means, and connecting means between said movable means whereby, when 30 any of said actuating means are operated, coins are discharged from one of the magazines the movable means associated with which are provided with actuating means, and the magazine the movable means for 35 which are not provided with actuating means, simultaneously, said coins from said two magazines being delivered at remote 40 points.

2. The combination, in a change-making 45 machine, with a case, a plurality of superimposed magazines, supports in said case beneath said magazines, and reciprocable slides between said magazines and supports, said slides being spring-actuated in one direction, and having openings therein to receive predetermined numbers of coins from 50 said magazines, of operating levers mounted in said case, arms rigidly connected with said levers, and links connecting said arms with said slides, there being as many arms and links for the operation of one of said 55 slides as there are arms and links for the operation of a plurality of the remaining slides, for each of which latter there is a single arm and a single link, the links which are connected to the same slide being slotted to enable such slide to be actuated by any one of such links without any other of such 60 links being affected.

65 3. The combination, in a change-making

machine, with a case, a plurality of superimposed magazines, supports in said case beneath said magazines, and reciprocable slides between said magazines and supports, said slides being spring-actuated in one direction, 70 and having openings therein to receive predetermined numbers of coins from said magazines, of a rock-shaft journaled in said case, a sleeve secured to said shaft and provided with a lever and an arm, a sleeve 75 loosely mounted on said shaft and provided with a lever and two arms, an arm secured to said shaft, connecting members between said two first-named arms and two said slides, and connecting members between said 80 two last-mentioned arms and another of said slides.

4. The combination, in a change-making machine, with a case, a plurality of superimposed magazines, supports in said case beneath said magazines, and reciprocable slides between said magazines and supports, said slides being spring-actuated in one direction, 85 and having openings therein to receive predetermined numbers of coins from said 90 magazines, of a rock-shaft journaled in said case, a sleeve secured to said shaft and provided with a lever and two arms, an arm secured to 95 said shaft, links connecting said two first-mentioned arms with two of said slides, and links connecting said two last-mentioned arms with another of said slides, said last-named links having longitudinal slots there- 100 in to enable either to be actuated without the other.

5. The combination, in a change-making machine, with a case provided with independent coin-chutes delivering at remote 105 points a fare-unit magazine and a change-unit magazine mounted on said case in operative relation to said coin-chutes, supports in said case beneath said magazines, and slides arranged to reciprocate between said 110 magazine and supports, said slides being spring-actuated in one direction, having openings therein to receive fare-units and change-units from said magazine, and adapted to deliver said fare-units and 115 change-units to said coin-chutes, of means simultaneously to operate said slides.

6. The combination, in a change-making machine, with a case provided with independent coin-chutes delivering at remote 120 points, and a fare-unit magazine and a plurality of change-unit magazines mounted on said case in operative relation to said coin-chutes, supports in said case beneath said magazines, and slides arranged to reciprocate in said case between said magazines and supports, said slides being spring-actuated in one direction, having openings therein to receive fare-units and change-units from 125 said magazines, and adapted to deliver said 130

fare-units and change units to said coin-chute, of means simultaneously to operate any one of the slides for the change-unit magazines and the slide for the fare-unit magazine.

7. The combination, in a change-making machine, with a case, superimposed coin magazines, platforms, posts adapted to support platforms at different elevations beneath said magazines, said posts having means whereby said platforms may be adjusted vertically and slides interposed between said magazines and platforms, said slides having openings therein above said platforms to receive different predetermined numbers of coins from said magazines, of operating means for said slides.

8. The combination, in a change-making machine, with a case, superimposed coin magazines, supports in said case beneath said magazines, slides interposed between said magazines and supports, and having openings therein to receive predetermined numbers of coins from said magazines, and operating means for said slides, of a rod journaled in said case, and provided with lugs to engage and lock, and release and unlock, said slides, accordingly as said rod be rocked to throw said lugs in one direction or the other.

9. The combination, in a change-making machine, with a case, a plurality of superimposed magazines, supports in said case beneath said magazines, and reciprocable slides between said magazines and supports, said slides being spring-actuated in one direction, and having openings therein to receive predetermined numbers of coins from said magazines, of a rock-shaft journaled in said case, a sleeve secured to said rock-shaft and provided with a lever and an arm, an arm secured directly to said shaft, and connecting members between said arms and said slides.

10. The combination, in a change-making machine, with a case, a plurality of superimposed magazines, supports in said case beneath said magazines, and reciprocable slides between said magazines and supports, said slides being spring-actuated in one direction, and having openings therein to receive predetermined numbers of coins from said magazines, of a rock-shaft journaled in said case, a sleeve loosely mounted on said shaft and provided with a lever and two arms, and connecting members between said arms and said slides.

11. The combination, in a change-making

machine, with a case, a plurality of superimposed magazines, supports in said case beneath said magazines, and reciprocable slides between said magazines and supports, said slides being spring-actuated in one direction, and having openings therein to receive predetermined numbers of coins from said magazines, of a rock-shaft journaled in said case, a sleeve loosely mounted on said shaft and provided with a lever and an arm, a sleeve secured to said shaft and provided with a lever and an arm, a sleeve mounted on said shaft and provided with a lever and two arms, an arm secured directly to said shaft, connecting members between said first-named arm and one of said slides, connecting members between said second-named arm and said arm which is secured directly to said shaft and two others of said slides, and connecting members between the arms which extend from the same sleeve and two of said slides, one of said last-named slides being that with which said arm is connected that is secured directly to the shaft, and the other being one not otherwise connected with any arm.

12. The combination, in a change-making machine, with a casing, a superimposed coin magazine, a post in said casing supporting a platform beneath said magazine, said post being provided with means for raising and lowering said platform, and a slide interposed between said magazine and platform, said slide having an opening therein to receive coins from said magazine, of operating means for said slide.

13. In a change-making machine, a magazine for a column of coins, delivery means for coins from said magazine, movable means in operative relation to said magazine, other magazines for columns of coins, delivery means for coins from said last-named magazines, said last-named delivery means opening at a point remote from the point at which said first-named delivery means opens, movable means in operative relation to each of last-named magazines, actuating means for said last-named movable means, and means whereby the actuating means associated with said first-named magazine is operated to deliver coins therefrom each time the actuating means associated with any of the others of said magazines is operated to deliver coins therefrom.
